UNITED STATES PATENT OFFICE.

SAMUEL H. MARKHAM, OF CLEVELAND, OHIO.

NUT-MACHINE.

SPECIFICATION forming part of Letters Patent No. 320,571, dated June 23, 1885.

Application filed October 10, 1884. (No model.)

To all whom it may concern:

Be it known that I, SAMUEL HENRY MARKHAM, a citizen of the United States, residing at Cleveland, county of Cuyahoga, and State 5 of Ohio, have invented certain new and useful Improvements in Nut-Machines; and I do hereby declare the following to be a description of the same, and of the manner of constructing and using the invention, in such full, clear, 10 concise, and exact terms as to enable any person skilled in the art to which it appertains to construct and use the same, reference being had to the accompanying drawings, forming a part of the specification, the principle of the 15 invention being herein explained and the best mode in which I have contemplated applying that principle, so as to distinguish it from other inventions.

My invention relates to nut-forging machines, and is an improvement therein. Said improvement is such that I thereby cut two blanks simultaneously from the bar and forge said blanks simultaneously into nuts, both said results being effected by one and the same forward operation of the machine; also, by an 25 immediate and direct continuance of said operation, the two said blanks are simultaneously discharged from the machine.

In the drawings, Figure 1 is a front perspective with the head-piece removed. Fig. 2 is a detail view of the head-piece. Fig. 3 is a rear elevation. Fig. 4 is a right-hand side elevation. Fig. 5 is a left-hand elevation. Fig. 6 is a plan view with certain top portions removed. Fig. 7 is a sectional detail view of the shears and of shear-block on line $x-x$ of Fig. 6. Fig. 8 is a detail view of a piercer, crowner, and die. Fig. 9 is a detail vertical sectional view of head-piece, taken in a plane passing 40 through one of the two duplicate sets of piercers and crowners.

A is the main driving-shaft, operated by power-wheel A'. Shaft A is provided with cams B C C' D D'. Cam B operates lever B'. Said lever operates lateral shaft B², journaled in head-piece O². Said shaft is provided with lugs b, engaging in slots b', formed in crowner-slides E', said crowner-slides, respectively, provided with crowners E and F. Said lever is 45 retracted by spring B⁴ engaging with pin B⁵, which projects from the side of said lever.

Cams C and C' operate the two rear hammer-slides, c c', in connection with the two bearing-arms M M', said arms being pivoted in shoes m, and designed to protect said hammer-slides 55 from the lifting tendency of said cams, said slides being armed with hammers s² and sliding in guideways c' and retracted by spring c'. Cam D operates lever P, which said lever operates upwardly shear-holder N, said holder 60 being provided with shear f, said shear-holder being retracted by lever d, which swings on gear-shaft d', and is operated by spring R. The shear-block S² holds the two upper shears, e e', which said shears are stationary. Cam 65 D' operates lever O, said lever journaled on pivot b², journaled in head-piece O², and connecting at its forward extremity with the depending piercer-holders G and H, said holders 70 provided with piercers e², said holders 75 rigid in a common slide, K. A yoke, K², fits over the front end of lever O, and has its dependent arms pivoted to said slide K. Slide K moves in slideways G². The rear end of lever O is provided with the depending retracting-arm L, which is operated by pin l, laterally projecting from cam D'. On shaft A' are the rigid pinions R' R², which engage with pinions S S', rigid, respectively, on the two end shafts, T T'. Shaft T is provided with the double cam 80 W W², operating hammer-slide i, and also with the single cam W', operating hammer-slide j. Shaft T' is provided with cam V, operating hammer-slide g, and also with the double cam V' V², operating hammer-slide h. Each hammer-slide g and j is retracted by a spring, m, 85 said spring working against a pin, m', depending from the under face of the outer extremity, respectively, of each of said slides. Hammer-slide h is provided at its rear extremity with 90 a laterally-projecting pin, n. A link, n', has its extremities, respectively, pivoted to the free end of said pin and to lever-arm p'. Said lever-arm engages pin n', projecting laterally from cam V', and is pivoted at its lower end 95 in shoe r', said lever-arm having bearing-arm p² for the protection of hammer-slide h. Hammer-slide i is retracted by mechanism that is the duplicate of the mechanism last recited. Hammer-slides g h j engage with bearing-arms 100 n², to prevent the lifting action of the impinging cams V and W', said arms being pivoted

in shoes r^3 , said hammer-slides $g\ h\ i\ j$ sliding in guide-ways $g'\ h'\ i'\ j'$, said hammer-slides provided with hammers s^2 .

$y\ y'$ are die-blocks upon which the blanks, 5 when cut, are shoved to be pierced. Front hammer-holders, $s\ s'$, are stationary, and provided with hammers s^2 .

t is the feeding-duct for the bars. At the outer end of each die-block $y\ y'$, respectively, 10 is the open orifice w , through which the forged nut falls in discharge from the machine. Gage s^3 stops the inserted bar at the desired point for the cutting of the blanks.

s^4 is a block on which the inner blank rests 15 preparatory to its being shoved by hammer of sliding hammer-holder i onto die-block y . The converging hammers of hammer-slides $g\ c\ i\ s'$ lie on a horizontal plane immediately below the horizontal plane of converging hammers of hammer-slides $h\ c\ j\ s$, the 20 said difference in said planes being demanded by the mechanism that cuts the two blanks by one operation of the combined shears, and that leaves them whence they can be shoved 25 by the hammers of hammer-slides h and i over upon the dies y and y' .

y^2 is the aperture in the die-blocks y and y' , upon which latter the nuts rest during the process of piercing and crowning, said die being 30 perforated for the passage of the piercer.

The following is the operation of my machine in the process of forging two nuts simultaneously: The bar being inserted by duct t and pushed inward between the shears and 35 shear-block N as far as gage s^3 , two blanks are simultaneously cut off by the upward movement of shear f , said shear being propelled by lever P , operated by cam D . Said blanks, by means of sliding hammers of hammer-slides $h\ i$, are then slid over respectively onto die-blocks $y\ y'$ under the crowners $E\ F$, where 40 they are struck by the converging hammers, and are also pierced by the piercers of holders $G\ H$, said hammer-slides $h\ i$ being operated by their respective cams, above specified, 45 on end shafts, $T\ T'$, and said piercers being operated by lever O by means of cam D' on shaft A . The piercers are then lifted by retracting appliances described. Crowners $E\ F$ are then 50 brought down upon the pierced nuts by lever B' , operated by cam B , which process gives a beveled top to the corners of the nuts. The crowners being then lifted by retracting appliances above described, the sliding hammers 55 of slides h and i still further advance and push the nuts off the die-blocks into the orifices w , through which they are discharged from the machine.

The converging hammers and the shear f 60 being then retracted by mechanism already described, the machine is ready for a repeating operation.

Other forms of embodying and using the principle of my invention may be employed 65 in substitution for the specific form herein shown. It will therefore be understood that omissions, substitution, and changes may be

made as regards the forms and parts herein set forth, provided the principles of construction embraced in the following claims are retained and employed.

I therefore particularly point out and distinctly claim as my invention—

1. In a nut-machine, the combination, with actuating machinery, of two sets of converging hammers, four hammers being in each set, and each several set converging separately, and two piercers and two crowners, all adapted to forge two nuts simultaneously and by one and the same operation of said machinery, substantially as set forth.

2. In a nut-machine, the combination, with actuating mechanism, of two sets of converging hammers, each said set consisting of four hammers, one said set lying in plane immediately under the plane in which the other said set lies, said combination adapted to forge two nuts simultaneously and by one and the same operation of the said mechanism, substantially as set forth.

3. In a nut-machine, the combination, with actuating mechanism, of two sets of converging hammers, said sets lying in different planes from each other and adapted to forge two separate nuts simultaneously, substantially as set forth.

4. In a nut-machine, the combination, with actuating mechanism, of two sliding hammers actuated by said mechanism, said hammers pushing two forged nuts simultaneously into two orifices provided in said machine, substantially as set forth.

5. In a nut-machine, the combination, with shaft A , provided with cam D , of lever P , operating shear-holder N , said holder retracted by lever d , which swings on shaft d^2 , and is operated by spring R , substantially as set forth.

6. In a nut-machine, the combination, with shaft A , interlocked by pinions with shafts $T\ T'$, said shafts being provided with cams $V\ V'$ and $W\ W'$, of converging hammer-slides $g\ h\ i\ j$, said slides armed with hammers s^2 , substantially as set forth.

7. In a nut-machine, the combination, with shaft A , provided with cam D' , said cam operating lever O , said lever journaled in head-piece O^2 , of slide K , yoked to the front end of said lever and having rigid with it the two piercer-holders $G\ H$, substantially as set forth.

8. In a nut-machine, the combination, with shaft A , provided with cam B , of lever B' , operating shaft B^2 , said shaft journaled in head-piece O^2 , and operating the two depending slides E' , with crowners $E\ F$ attached, substantially as set forth.

9. In a nut-machine, the combination, with shaft A , interlocking by pinions with shafts $T\ T'$, shaft T provided with cams $W\ W'$, and shaft T' , provided with cams $V\ V'$, of the four lateral sliding hammer-holders, $g\ h\ i\ j$, said holders armed with hammers s^2 , substantially as set forth.

10. In a nut-machine, the combination, with

shaft A, provided with cams C C', and bearing-arms M M', of sliding hammer-holders *c c'*, armed with hammers *s*², substantially as set forth.

5 11. In a nut-machine, the combination, with shaft A, interlocked by pinions with shafts T T', shaft T being provided with the double cam W W², and shaft T' provided with double cam V V², of sliding hammer-holders *i i'*, 10 armed with hammers *s*², said hammers on said

sliding hammer-holders being adapted to push forged nuts into orifices *w*, substantially as set forth.

In testimony that I claim the foregoing to be my invention I have hereunto set my hand 15 this 6th day of August, A. D. 1884.

SAMUEL H. MARKHAM.
